DESIGN FOR A BOX FOR PAPER TISSUES OR SIMILAR ACCESSORIES

Maxwell R. Feinberg and Howard V. Rosenblum,
New York, N. Y.

Application May 10, 1941, Serial No. 100,890

Term of patent 3½ years

To all whom it may concern:

Be it known that we, Maxwell R. Feinberg and Howard V. Rosenblum, citizens of the United States and residents of the city, county, and State of New York, have invented a new, original, and ornamental Design for a Box for Paper Tissues or Similar Accessories, of which the following is a specification, reference being had to the accompanying drawing, forming part thereof.

Figure 1 is a perspective view of a box for paper tissues or similar accessories, showing our new design, the cover flap of the container being shown in its closed position;

Figure 2 is a view similar to Figure 1 but showing the cover flap of the container in its raised or open position; and

Figure 3 is a sectional view taken substantially on the line 3—3 of Figure 1, looking in the direction of the arrows.

The stipple shaded portions of the box shown denote a contrasting appearance of such portions relatively to the other portions of the box.

The dominant features of our design are shown in full lines.

We claim:

The ornamental design for a box for paper tissues or similar accessories, as shown and described.

MAXWELL R. FEINBERG.
HOWARD V. ROSENBLUM.
